UNITED STATES PATENT OFFICE.

AUGUST DE KLEIST AND FRANK L. McCORMICK, OF NORTH TONAWANDA, NEW YORK,
ASSIGNORS TO THE RUDOLPH WURLITZER MANUFACTURING COMPANY, OF NORTH
TONAWANDA, NEW YORK, A CORPORATION OF NEW YORK.

FEED MECHANISM FOR PERFORATING-MACHINES.

1,085,986.

Specification of Letters Patent.

Patented Feb. 3, 1914.

Application filed April 5, 1911. Serial No. 619,058.

To all whom it may concern:

Be it known that we, AUGUST DE KLEIST and FRANK L. McCORMICK, citizens of the United States, and residents of North Tonawanda, in the county of Niagara and State of New York, have invented new and useful Improvements in Feed Mechanism for Perforating-Machines, of which the following is a specification.

10 This invention relates to a feed mechanism designed more especially for feeding sheets or webs past the punches of perforating machines in the production of perforated music sheets for automatic musical instruments, but the mechanism may be used in connection with other machines and for feeding other articles, if desired. In such instruments the music sheet is caused to travel at an accelerated or gradually increased speed from the usual music roll to the take-up roll by reason of the gradually increasing diameter of the take-up roll, with the result that the music is played at an increasing tempo toward the tail end of the 20 sheet, this being especially objectionable in the case of musical instruments used in dancing halls and skating rinks where it is necessary to maintain a uniform tempo. In order to overcome this objection it has been proposed to feed the sheets past the punches at a gradually-increasing speed corresponding to the accelerated speed with which the sheet is subsequently caused to travel in the instrument, thus punching the perforations 30 farther and farther apart from the front toward the rear end of the sheet and compensating for such irregularity of its movement.

It is the object of our invention to produce a positive feed mechanism for perforating 40 machines of this type by which such graduated punching of the perforations is effected in a reliable and accurate manner.

In the accompanying drawings consisting of 4 sheets: Figure 1 is a vertical longitudinal section of a perforating machine embodying the invention. Fig. 2 is a fragmentary side elevation of the sheet feeding mechanism. Fig. 3 is a top plan view thereof. Fig. 4 is a longitudinal section on line 45 4—4, Fig. 3. Fig. 5 is a similar section on line 5—5, Fig. 3. Fig. 6 is a transverse section on line 6—6, Fig. 2. Figs. 7 and 8 are sections on lines 7—7 and 8—8, Fig. 2. Fig.

9 is a longitudinal section, on an enlarged scale, on line 9—9, Fig. 6.

55

Similar letters of reference indicate corresponding parts throughout the several views.

Generally speaking, such perforating machines usually include a suitable punching mechanism, rolls for guiding and feeding a perforated master sheet which controls the selection of the punches, and feed mechanism for moving one or more sheets to be perforated past the punches. This punch mechanism and the devices for feeding the master sheet form no part of our present invention and may be of any suitable or approved construction.

In the machine shown in the drawings, A indicates the stationary bed, B the punches, C the master sheet, C¹ the main feed roll of said sheet, and D the main driving shaft of the machine.

E indicates the sheets or webs to be perforated which are supported upon the bed A, and E¹ are the supply rolls upon which supply such sheets are wound. From the punching mechanism, the superposed sheets pass between the gripping devices of a feeder which preferably consists of endless belts or chains F running around front and rear sprocket wheels f and carrying transverse bars or grippers f¹ having facings f² of rubber or similar material. Two sets of 80 such traveling grippers are arranged above and below the sheets or webs E and the grippers of the two sets of chains are arranged to come into register at the opposing sides of the chains, so as to grip the sheets 85 between them and feed them past the punches. While we prefer the feeder shown in the drawings, we do not wish to be limited to this particular construction, as other forms of gripping devices which seize or engage opposite sides of the webs or sheets to be punched may be employed, if desired, without departing from our invention.

The shafts g, g¹, g², g³ of the sprocket wheels f are supported in bearings carried 100 by a bracket or table G secured to the bed A and the upper rear shaft g is driven from the corresponding lower shaft g² by gear wheels g⁴, g⁵. The lower shaft g² of the feeder is intermittently driven by the following 105 mechanism: h is an intermittently-rotated

gear wheel mounted on a transverse shaft or stud h^1 secured to the adjacent bracket G, said wheel being preferably held on said stud by a bushing h^2 and a clamping nut h^3 . Motion is transmitted from the wheel h to the feeder shaft g^2 by an idler gear h^4 and a gear wheel h^5 secured to the shaft g^2 , as shown in Fig. 4. This idler is carried by an oscillating arm h^6 pivoted upon the stud h^1 and clamped in position by a bolt h^7 screwed into the bracket G and passing through a curved slot h^8 in said arm. Upon loosening this bolt, said idler can be swung out of mesh with the gear wheel h^5 to stop the feeder. I is a ratchet wheel secured to the hub of the gear wheel h and engaged by a series of feed pawls j carried by a wheel or disk J secured to the hub of an oscillating arm or member K, these parts constituting a clutch. Said hub is supported upon the bushing h^2 . The arm K, which is preferably hollow, is vibrated from the main shaft D by an eccentric k and a connecting rod k^1 . The rear end of this rod is coupled to the vibrating arm K by a connection which is gradually and automatically shifted from the free upper end of said arm toward its pivot h^1 , as the punching operation progresses, to gradually increase the stroke of said arm and of the feeder actuated thereby, thus correspondingly increasing or graduating the spaces between the holes punched in the sheets. In the preferred construction shown in the drawings, this traveling connection consists of a nut or follower L attached to the rear end of said rod by a transverse pin l passing through the rod and a lug l^1 projecting from the rear side of the nut. This nut traverses a rotary feed screw M arranged in the hollow arm K and journaled in bearings m , m^1 at the upper and lower ends thereof, said screw being held against longitudinal movement on the arm by collars or shoulders on said screw, as shown in Figs. 5 and 6. Fixed to the projecting upper end of this screw is a spur gear n meshing with a corresponding pinion n^1 secured to a short shaft n^2 arranged parallel with the screw and mounted on a bracket N projecting inwardly from the upper end of the arm K. Secured to the last-named shaft above its pinion n^1 is a ratchet wheel o which is arranged to encounter an actuating pawl o^1 pivoted to a standard or fixed support P mounted on the table G, so that on the backward stroke of the oscillating arm K the toothed edge of said ratchet wheel strikes the nose of said pawl, rotating said wheel the distance of a tooth, turning the feed screw M a corresponding distance through the medium of the gear wheels n , n^1 and shifting the nut L toward the pivot of the arm K accordingly. A correspondingly longer stroke is thereby imparted to the ratchet wheel I

and by the latter to the traveling grippers f^1 through the medium of the gear wheels h , h^4 and h^5 . Upon the forward stroke of the arm K, the ratchet wheel o rides idly over the pawl o^1 . Backward movement of the ratchet wheel o is prevented by a detent pawl o^2 . 70

It will be observed from Figs. 5 and 8, that the lug l^1 of the nut L passes through a longitudinal slot h^2 in the hollow arm K, thus holding it against turning on the feed screw M. 75

In order to permit the ratchet wheel o to be thrown out of action, if desired, the shaft n^2 is made vertically-movable in the bracket N so that the said wheel can be raised clear of the pawl o^1 . This shaft is locked in its operative and inoperative positions by a spring latch q adapted to engage either of a pair of grooves n^3 , n^4 in said shaft, as shown in Figs. 6 and 8; or by any other suitable means. 80

The operation of the machine is as follows: Before beginning the punching of the sheets, the nut L is returned to its uppermost or initial position by rotating the feed screw M either by a hand tool or by attaching to its upper end a suitable power-driven head or socket to save time. Upon starting the machine, the connecting rod k^1 is reciprocated with a uniform stroke by the eccentric k . The shaft h^1 is intermittently turned forward by the oscillating arm K through the feed pawls j and ratchet wheel I, thus moving the opposing portions of the feed chains F forward in unison and causing their grippers f^1 to feed the sheets past the punches in an obvious manner. Upon each forward stroke of the arm K, the ratchet wheel o rides idly over the corresponding pawl o^1 , but upon the return stroke of said arm, the abrupt side of one of the teeth of said ratchet wheel is tripped by the nose of said pawl and turned forward the distance of a tooth, rotating the feed screw M a step and shifting the nut L toward the arm-pivot h^1 , as hereinbefore described. This obviously increases the stroke of the arm K attached to the pawl disk J, with the result that the grippers f^1 are caused to advance with a correspondingly longer stroke or step. In this manner the nut L approaches said arm-pivot more closely with each stroke of the arm, accelerating the movement of the feeder in the same measure and gradually widening the spaces between the successive holes punched in the sheets toward the tail ends of the latter. 100 105 110 115 120

To reduce lost motion between the ratchet disk I and its actuating pawls j to a minimum, a comparatively large number of fine teeth is preferably employed on said wheel in connection with a comparatively large number of pawls, as shown in Fig. 9. Very satisfactory results have been obtained with 130 125

5 a ratchet wheel having one hundred and forty-one teeth and twenty coöperating pawls. This produces a practically positive and non-slipping feed, inasmuch as one of the pawls is always in engagement with a tooth of the ratchet wheel ready to turn it with practically no lost motion.

10 As the sheets to be perforated are not wound upon a take-up roll but are fed onward by gripping or holding devices which reliably engage opposite sides thereof, the sheets are kept at a practically uniform tension at all times, insuring punching of the same with the required accuracy.

15 A frictional detent or holding device is preferably employed to prevent backlash or backward movement of the feeder-chains under the tension of the sheets, as well as avoid overthrow or excessive forward movement of the feeder. For this purpose, we preferably interpose a retarding or brake-disk r of felt, or other suitable material between the inner face of the hub of the gear wheel h and the arm h^o . By means of the 20 nut h^s and the bushing h^2 , the driving gear of the feeder can be pressed more or less tightly against said disk r , to accomplish this result.

We claim as our invention:

30 1. A sheet feeding mechanism, comprising a feeder adapted to engage the flat side of the sheet, and driving mechanism for said feeder including automatic means for accelerating the movement of the feeder from the beginning to the end of the feeding operation.

40 2. A sheet feeding mechanism, comprising a feeder adapted to engage the sheet, means for intermittently actuating the feeder, driving mechanism, and an operative connection between the feeder and said driving mechanism including automatic means for gradually increasing the stroke of said actuating means from the beginning to the end of the feeding operation.

50 3. A sheet feeding mechanism, comprising a feeder adapted to engage the sheet, an oscillating member operatively connected with said feeder, a part movable on said oscillating member toward and from its pivot, means controlled by the oscillating movement of said member for shifting said movable part thereon, actuating mechanism for said member, and an operative connection between said actuating mechanism and said movable part.

60 4. A sheet feeding mechanism, comprising a feeder adapted to engage the sheet, an oscillating member operatively connected with said feeder, a rotary screw carried by said oscillating member, automatic means for turning said screw, a nut traversing the screw, actuating mechanism for said member, and an operative connection between 65 said actuating mechanism and said nut.

5. A sheet feeding mechanism, comprising a feeder adapted to engage the sheet, an oscillating member operatively connected with said feeder, a rotary screw mounted radially on said member, a trip device arranged in the path of movement of said oscillating member for rotating said screw, a nut traversing the screw, driving mechanism, and means operatively connecting said nut with said driving mechanism. 70

6. A sheet feeding mechanism, comprising a feeder adapted to engage the sheet, an oscillating member operatively connected with said feeder, a rotary screw mounted radially on said member, a ratchet wheel connected with said screw and carried by said member, a relatively-stationary feed pawl coöperating with said ratchet wheel, a nut traversing said screw, driving mechanism, and an operative connection between 80 said nut and said driving mechanism. 75

7. A sheet feeding mechanism, comprising a feeder adapted to engage the sheet, an oscillating member operatively connected with said feeder, a rotary screw mounted on 90 said member, a ratchet wheel connected with said screw, a relatively stationary feed pawl coöperating with said ratchet-wheel, a nut traversing said screw, driving mechanism, and an operative connection between 95 said nut and said driving mechanism. 90

8. A sheet feeding mechanism, comprising a feeder adapted to engage the sheet, an oscillating member operatively connected with said feeder, a rotary screw mounted on said member, a ratchet wheel connected with said screw, a relatively stationary feed 100 pawl coöperating with said ratchet-wheel, a nut traversing said screw, driving mechanism, and an operative connection between 105 said nut and said driving mechanism, said ratchet wheel being mounted on said member and axially movable thereon to clear said pawl and throw said wheel out of operation. 105

110 9. A sheet feeding mechanism, comprising a feeder adapted to engage the sheet, an oscillating member operatively connected with said feeder, a rotary screw carried by said member, a shaft geared with said screw and carrying a ratchet wheel, said shaft being slidably mounted on said member, a relatively stationary feed pawl coöperating with 115 said ratchet wheel, a nut mounted on said screw and an actuating rod connected with said nut. 120

10. A sheet feeding mechanism, comprising a feeder adapted to engage the sheet, an oscillating member operatively connected with said feeder, a rotary screw carried by said member, a shaft geared with said screw and carrying a ratchet wheel, said shaft being slidably mounted on said member and 130

having locking grooves, a latch arranged to engage with either of said grooves, a feed pawl coöperating with said ratchet wheel, a nut mounted on said screw, and an actuating rod connected with said nut.

11. A sheet feeding mechanism, comprising a feeder adapted to engage the sheet, an actuating gear for said feeder, means for driving said gear, and frictional detent means engaging said gear.

12. A sheet feeding mechanism, comprising a feeder adapted to engage the sheet, a screw threaded stud carried by a fixed support, an actuating gear for said feeder mounted on said stud, a clamping nut applied to said stud and operating to clamp said gear against said support, and means for driving said gear.

13. A sheet feeding mechanism, comprising a feeder adapted to engage the sheet, a screw threaded stud carried by a fixed support, an actuating gear for said feeder mounted on said stud, a clamping nut applied to said stud, a bushing arranged on said stud between said nut and said gear, an oscillating arm mounted on said bushing, means for actuating said arm, and a clutch connecting said gear with said arm.
